UNITED STATES PATENT OFFICE.

HUGO BILGRAM, OF PHILADELPHIA, PENNSYLVANIA, ASSIGNOR, BY MESNE ASSIGNMENTS, TO THE EASTERN PAPER BAG COMPANY, OF HARTFORD, CONNECTICUT.

PAPER-BAG MACHINE.

SPECIFICATION forming part of Letters Patent No. 634,102, dated October 3, 1899.

Application filed July 22, 1898. Serial No. 686,590. (No model.)

To all whom it may concern:

Be it known that I, HUGO BILGRAM, of the city and county of Philadelphia, State of Pennsylvania, have invented an Improvement in 5 Paper-Bag Machines, of which the following is a specification.

My invention relates to paper-bag machines; and it consists of certain improvements which are fully set forth in the following specification and are shown in the accompanying drawings.

I have shown my improvements embodied in an organized machine adapted for forming a completely folded and pasted bag from a 15 continuous roll of paper, and my improvements are especially adapted to the formation of a "satchel-square" bottom upon a bellows side-fold tube.

A part of my improvements relates to the 20 tube-forming devices by which the paper is formed into a pasted tube and is designed particularly to equalize the tension upon the paper throughout the tube-forming devices while the tube is being formed, whereby 25 wrinkling and tearing of the paper are avoided and a perfect continuous tube may be formed at a very high speed.

Another part of my invention relates to the 30 slitting devices used in machines of this character for making slits in the paper tube at intervals to form tabs upon the ends of the tube-sections, and this part of my invention is designed especially for controlling the 35 operation of such slitters, whereby their speed may be regulated to suit the speed with which the paper is moving, whether it be faster or slower, and their time of operation may be suitably regulated to insure the slits being made at the proper intervals apart.

40 Another part of my invention relates to the cutting devices; and it consists particularly in certain improvements in the swinging cutter-bar or striker and in the means for operating it, whereby the line of movement of the bar or striker is confined wholly within the 45 body of the machine.

Another part of my invention relates to the 50 bottom-formers by which the end of the paper tube is formed into the proper folds before passing to the final-folding and pasting devices, and this part of my invention is de-

signed particularly for enabling a satchel-square bottom to be formed on a bellows side-fold tube by the action of suction with great rapidity and precision. This part of my invention also includes improvements in the means for applying the suction to the suction-formers by which the bottom is folded, whereby the use of external suction-tubes leading to the suction-formers is avoided. 55 60

My invention also relates to the devices for clamping the tube-sections while their ends are being folded by the bottom-formers and automatically releasing them after the bottom folds are formed, and these improvements are designed to attain greater simplicity of construction and certainty of action. 65

Another part of my invention relates to the final-folding and pasting devices and is designed to enable the final folds, which are 70 formed in the paper tube after it is delivered from the bottom-formers, to be made with greater accuracy and speed.

Another part of my invention relates to printing devices for printing an impression 75 upon the paper bags during their process of construction—*e. g.*, for indicating the capacity thereof—and this part of my invention is designed especially for controlling the operation of such printing devices to suit the 80 speed of movement of the paper and for timing their operation so that the impressions may be made at the proper intervals.

My invention also embraces improvements in the stripping devices for removing the partially-formed tube-section from the bottom-forming devices, whereby a more positive and certain action of the gripper of the stripping-cylinder is obtained. 85

I shall now refer to the accompanying drawings, in which— 90

Figure 1 is a side elevation of a paper-bag machine embodying my invention. Figs. 2 and 2^a show a plan view of the same on a larger scale than Fig. 1. Figs. 3 and 3^a show 95 a longitudinal vertical sectional view of the same on the line *xx* of Figs. 2 and 2^a. Fig. 3^b is a sectional view similar to Fig. 3 of a part of the mechanism, showing the tucker-plate in a different position. Fig. 4 is a transverse 100 vertical sectional view on the line *yy* of Fig. 1, looking to the right. Fig. 5 is a plan view,

enlarged, of the tube-section carrier and bottom-former. Fig. 6 is a front view of the same with the suction-formers opened. Fig. 7 is a transverse sectional view of one of the formers on the line *z z* of Fig. 6. Fig. 8 is a side elevation of the tube-section carrier and bottom-former. Fig. 9 is a longitudinal vertical sectional view of the same on the line *w w* of Fig. 5. Fig. 10 is a front elevation, enlarged, 10 of part of the final-folding devices. Fig. 11 is a vertical sectional view of the same on the line *v v* of Fig. 10. Fig. 12 is a detail plan view of a part of the devices for operating the folding-plates. Fig. 13 is a cross-sectional view of the same on the line *u u* of Fig. 12. Fig. 14 is a plan view, enlarged, of the stationary guide-plate and the movable base of the reciprocating carrier. Fig. 15 is a transverse vertical sectional view of the same on the line *t t* of Fig. 14. Fig. 16 is a sectional diagram of the final-folding and pasting cylinders. Fig. 17, Sheet 5, is a plan view, enlarged, of the printing devices. Figs. 18 and 19 are longitudinal sectional views of the suction-formers, showing different positions assumed by the sections in the formation of the bag-bottoms. Figs. 20 and 21 are transverse sectional views of the tube-forming devices, respectively, on the lines *r r* and *s s* of Fig. 2^a. 25 Figs. 22, 23, 24, 25, 26, 27, and 28 are perspective views of the tube-section, illustrating the different steps in the formation of the bag-bottom. Fig. 29, Sheet 7, is a horizontal sectional view of a part of the bottom-formers, 30 showing the air-passage-way therein. Figs. 30, 31, 32, 33, 34, and 35 are perspective views of detached portions of the bottom-formers. Fig. 36 is an end view, enlarged, of the stripping-cylinder; and Fig. 37 is a longitudinal sectional view of part of the same on the line *p p* of Fig. 36.

The body of the machine is composed of suitable side frames 11, by which the various operative parts are carried. The final-folding and pasting devices are carried in brackets 22 at the front of the machine.

Power is distributed to the various operative parts of the machine through suitable gearing and power-transmitting connections from 45 a power-shaft 3, journaled in the frames 11.

The paper in a continuous web is taken from the roll 4, mounted in the rear of the machine, and is carried forward about suitable guides, pasted longitudinally, and folded 50 into a bellows side-fold tube. It is then cut into sections, which are taken by the reciprocating carrier, and the bottom folds are formed by the movable suction-formers thereof. These tube-sections, with the bottoms 55 thus partially formed, are then delivered to the final-folding and pasting devices, by which the final-folding and pasting operations are performed, and the finished bags are discharged from the machine.

60 *The tube-forming devices*, (see Figs. 1, 2^a, 3^a, 20, and 21.)—The roll of paper 4 is carried on a shaft 5, supported in brackets 6 in

the rear of the machine. It passes thence in a continuous web over a guide 7, extending transversely between the frames 11, and upon 70 a guide 8 in the rear of the machine, adjacent to which is located the paste-wheel 9, by which paste is applied in the usual manner to one of the edges of the web as the paper passes over the guide 8. From the guide 8 75 the paper passes under the forming-plate 10, which is carried by a frame 11, supported by a pendant 12 from a bracket 12^a, carried by one of the side frames 1, and forms an upwardly-inclined extension from the rear of 80 the base-plate 14. This plate or extension 10 has outwardly-inclined edges 13 13, by which the sides of the web are bent upwardly in commencing the formation of the tube. (See Fig. 20.) The lower face of the frame 85 11 carries a base-plate 14, inclining upwardly from the base of the plate or extension 10 and forming therewith an angle 15. Under this plate 14 and its extension 10 the paper of the web passes while its edges are being folded 90 down and the bellows folds are being formed in the sides. 95 The top plate, carried by the frame 11 and extending forward between the feeding-rolls 25 26, one of which is suitably reduced, as at 25^a, to admit it.

100 17 is a folding-finger carried by the arm 12^a and extending forward with an inwardly-inclined edge over the plate 16 from the end thereof on one side.

105 18 is a folding-finger carried by the arm 12^a on the opposite side and extending rearwardly, with an inclined edge over the plate 16 from the end thereof.

110 19 19 are fingers (shown as extensions of the fingers 17 18) projecting rearwardly beyond the end of the plate 16 and inclining outwardly.

115 20 is a finger carried by the plate 16 and projecting from its opposite side over the finger 17.

120 21 21 are plates carried by the bracket 12 or pendant 12^a and extending forward longitudinally one on each side under the plate 16 with their edges inclining forwardly from the rear.

22 are guides, one on each side, depending from the fingers 17 and 18 and located at the sides between the plates 14 and 16 and adjacent to the extension 10.

125 As the web of paper passes under the plate 10 its two sides are bent up by the inclined edges 13 13 thereof, the downward inclination of the plate, together with the inward inclination of the edges 13 13, acting to turn up the side edges. This action is also assisted by the fingers 19 19, which act upon the outside of the paper and serve to hold it in contact with the edges 13 13 of the plate 10. The outward inclination of these edges 13 13 acts 130 to gradually narrow the lower ply of the paper until it reaches the base-plate 14, where its upturned sides pass under the guides 22 22 and the side edges at the top pass under the

5 fingers 17 and 18. (See Fig. 21.) By these means an even tension is obtained upon the paper throughout and the liability of the paper to wrinkle or to be torn is avoided. The sides of the paper are acted upon by the plates 21 21, and being wide at the rear where they pass the angle 15 are gradually creased inwardly to form the bellows side folds. The finger 17 folds the edge upon which it acts 10 down upon the plate 16, while the finger 20 acts upon the opposite pasted edge and folds it over. The bellows-tube thus formed envelops the plate 16, and as it travels forward to the rolls 25 26 its upper face is acted 15 upon by the rollers 23 23, which serve to draw the paper tightly about the upper plate. The rollers 23 23 are shown set at an angle and carried by a weighted lever 24, supported by a pedestal 27.

20 The fingers 19 19 may be omitted or used on one side only, and while the fingers 22 22 are desirable in assisting in flattening down the sides and guiding the paper they may be omitted without materially affecting the operation of the tube-former.

25 37 is a plate arranged over the forward end of the plate 16 immediately in the rear of the rolls 25 26, between which and the plate 16 the upper ply of the paper tube passes. This 30 plate serves to keep the paper flat and to prevent creasing and also to press the pasted edges together. This plate is shown provided with side flanges 38, extending downward on each side of the plate 16 and held 35 against forward movement by the rod 39. In the construction shown the pedestal 27 for the pressure-roll lever 24 is carried by this plate 37, and the plate is provided with slots 40 40 to admit the slitters 28.

40 41 is a pressure-plate located below the plate 14, between which and the plate 14 the lower ply of the paper tube passes. This plate is shown hinged to the end of a lever 42, carried on the rod 39, and an arm 43, carried 45 thereby and connected by a spring 44 with a stationary portion of the machine, holds the plate 41 in contact with the lower ply of the paper tube as it passes over the plate 14. The plate 41 acts to hold the paper tube flat 50 and to prevent creasing.

55 *The slitters and means for controlling them, (Figs. 2^a and 3^a.)*—28 are the slitters for cutting the short longitudinal slits in the paper tube to form the tabs on the ends of the tube-sections when the tube is severed. As these slitters must operate to make the slits exactly at the lines upon which the tube is severed into bag-lengths, it is desirable that their 60 time of action should be varied with any change in the length of the bag-sections to make the slits at greater intervals apart. It is also desirable to prevent any irregularity in cutting or variation in the length of the slits that their speed of operation should be 65 uniform with the speed of movement of the paper.

To control the intervals of the action of the

slitters, I employ means for interrupting their operation, and to enable their speed of operation to be maintained uniform with the speed of movement of the paper I control their speed through power-transmitting connections with the tube-feeding or drawing-in devices, so that whatever may be the speed of movement of the paper the slitters will 70 operate uniformly therewith, while their intervals of action may be varied to suit the length of the bag-sections to be formed.

75 The slitters 28 are carried on a shaft 29, journaled behind the rolls 25 26 in suitable 80 bearings on the side frames 1 1 and driven through a gear-wheel 30, carried thereby, which engages a gear-wheel 31, loose on a counter-shaft 32 and controlled by the tube-feeding or drawing-in devices, receiving 85 power from the gear-wheel 212 on the shaft of the lower drawing-in roller 26 through an intermediate gear 211.

90 The devices shown for interrupting the action of the slitters 28 are as follows: The gear-wheel 30 is connected with the shaft 29 or with the sleeve 33 thereon, which carries the slitters, by a yielding connection through a spring 34, and a finger 35, carried by the shaft, is acted upon by a segment 36 on the counter-shaft 32, which during the interval 95 of its contact with the finger 35 prevents the rotation of the shaft 30 and slitters 28, putting the spring 34 under tension, which the instant the segment 36 releases the finger 35 100 restores the driving connection between the shaft 29 and slitters 28. The gear-wheel 30 continues the rotation of the shaft 29 until its movement is again arrested by the action of the segment 36 on the finger 35.

105

110 To regulate the action of the segment 36 to govern the operation of the slitters 28 28 and release them at the proper moment with relation to the movement of the paper, it may be adjusted circumferentially on the shaft 32.

When the speed of the drawing-in rollers 25 26 is accelerated or retarded to increase or decrease the speed of movement of the gear 30, the slitters 28 will be correspondingly increased or decreased through the gearing 115 212, 211, and 31, and time of rest or interval of interruption will be correspondingly increased or diminished.

120 *The tube feeding and cutting devices, (Figs. 2, 2^a, 3, and 4.)*—25 26 are the drawing-in rollers, between which the paper tube passes and by which it is fed to the cutters, by which it is cut into bag-sections. The plate 16 passes between the rollers 25 26 and is formed at this point with a narrow section 16^a, so that 125 the rollers may act directly upon the sides of the paper. These rollers 25 26 are the feed-rollers by which the paper is drawn from the roll 4 and carried through the tube-former. They are journaled in suitable bearings on 130 the side frames 1 1, and the upper roller 25 is shown journaled in eccentrics, by which it may be raised out of contact with the lower roller 26, thus stopping the feeding of the

paper. The roller 25 is geared with the shaft 47 of the roller 26 by gears 48 49 and is driven therefrom.

The outer end of the plate 16 beyond the rollers 25 26 is provided with the usual serrated edge 59, and a second stationary cutter 70, carried by a bar 71, is located immediately above it. The bar 71 is shown pivoted to a bracket on the frame, as at 72, and its free end engages 10 a notch 73 on the opposite side and is locked in place by a pivoted dog 74, Fig. 4.

45 is a rocking reciprocating cutter-bar which in its cutting action is projected across the path of the paper tube and rocked past the stationary cutters and on its return movement is retracted and rocked back out of the path of the paper. The rocking movements are obtained by a crank operatively connected with the rear end of the bar, and the 20 reciprocations are imparted by a rocking slide on which the bar moves longitudinally when rocked. In the particular construction shown the cutter-bar 45 is pivoted or otherwise operatively connected at its rear end with a 25 crank 75 of a shaft 76, journaled in a bracket 77, carried by the side frame 1, and its rear portion is provided with a longitudinal slot 78, which receives a slide 79, pivoted on a stud 80 on the bracket 77. As the crank 75 30 turns the cutter-bar is rocked and at the same time is reciprocated on the slide 79. Considering the bar in the position shown in Fig. 4, the forward movement of the crank reciprocates the bar forward on the slide 79 until its 35 end extends below the stationary cutters 59 70. In this position the slide 79 is at the rear end of the slot 78, and the downward movement of the crank 75 rocks the bar on the stud 80 as a fulcrum, causing it to ascend 40 with a quick movement across the face of the cutters 59 70 and sever the paper tube. The continued forward and upward movement of the crank 75 retracts the bar 45 on the slide 79 until its end is moved beyond the line of 45 the cutters, and the further upward and forward movement of the crank then rocks the bar downward on the stud 80 as a fulcrum until it again reaches the position shown in Fig. 4. By these means the movements of 50 the bar 45 are confined within the planes bounding the sides of the machine, and the swinging of the bar in an arc outside of the machine, which requires lateral space and is dangerous, is avoided. The crank-shaft 76 55 may be operated from a counter-shaft 81 by worm-gears 250 251, carried by the crank-shaft and counter-shaft, respectively.

82 83 are feeding-rollers carried on shafts 84 85, respectively, and located in front of 60 the cutters, which receive the cut bag lengths and feed them forward to the bottom-formers. The shafts of these feed-rollers are geared together by gears 86 87.

88 is a guide-plate extending from the rear 65 of the feed-rollers 82 83 and between them forward to the point of delivery to the clamp-

frame of the carrier. The peripheries of the feed-rolls are suitably recessed to permit the passage of the guide-plate between them. The tube-sections, cut off by the action of 70 the bar 45, are fed forward by the rollers 82 83 over the plate 88, the rear end of which, 89, may be bent downward to guide the forward ends of the paper tubes and prevent them from catching thereon. 75

89 90 are feed-rolls located near the front end of the guide-plate 88 and running in contact with lower feed-rolls 90 90 to receive the tube-sections from the feed-rolls 82 83 and deliver them to the clamp-frame of the 85 bottom-formers. The feed-rolls 89 are shown above the plate 88 and the rolls 90 below it, the plate being provided with slots 91, through which the rolls make contact. Either or both of the sets of feed-rolls 89 and 90 may be provided with facing of more or less adhesive material, such as rubber. In the drawings the upper feed-rolls 89 are shown provided with rubber peripheries 92.

The shaft 93 of the lower rolls 90 is shown 90 driven by a gear-wheel 94, and the shaft of the upper rolls 89 is shown driven therefrom by gears 252.

The bottom-formers, (Figs. 1, 2, 3, 5, 6, 7, 8, 9, 14, 15, 18, 19, and 30 to 35.)—This portion of my invention relates to improvements upon the bottom-forming devices for forming satchel-square bottoms upon bellows side-fold tubes, described in Letters Patent to William B. Purvis, Nos. 519,348 and 519,349, dated 100 May 8, 1894; No. 530,650, dated December 11, 1894, and No. 578,361, dated March 9, 1897. In those patents are described bottom-forming devices employing a reciprocating carriage carrying suction-formers composed of hollow 105 sections, which during their reciprocations are moved apart and changed in the angular relations of their sections to break down the end of the paper tube into the desired folds. In connection therewith side-folding fingers 110 are used, adapted at certain intervals to move over the perforated faces of the suction-formers to assist the suction thereof in properly shaping the bellows side folds. As shown in those patents, the suction is created in the 115 hollow sections of the formers through flexible tubes connected with them. The tube-sections are fed to the carriage and are clamped thereby, with the ends projecting between the suction-formers, while the bottoms are being folded and are then released and stripped off. 120

A portion of my improvements relates to the employment of a clamping device on the carriage controlled by a frictional resistance 125 produced by the movement of the carriage to close the clamp during the forward reciprocation of the carriage while the bottom is being formed and to automatically open or release at the proper moment. For this purpose I employ a movable clamp upon the carriage operated by a controller slide or shoe 130

upon a guide, which imposes a frictional resistance to the controller and operates the clamp while the carriage is reciprocating.

50 is the reciprocating carriage guided in 5 guides 52 of a bed-frame 51, carried by the side frames 11.

53 is a pedestal carried by the carriage 50 and carrying the suction-formers 60 61. The carriage 50 is reciprocated by a lever 54, hinged 10 to the carriage, as at 55, and operated through a link 56 from a crank 57 on the shaft 58.

95 is a transverse plate carried by the pedestal 53 (or plates 62 62^a carried thereby) and projecting forward therefrom at a slight distance above the upper edge of the pedestal to permit the tube-sections to pass between. The rear faces of plate 95 and pedestal may be inclined or beveled, as shown, to guide the forward edge of the tube-section between 20 them.

96 is a clamp extending transversely below the projecting edge of the plate 95 and separated a distance therefrom to permit the tube-section to pass between. Its front edge is 25 immediately adjacent to the edge of the plate 95. This clamp 96 is pivoted at its rear, as at 100, to the plate 95 and is provided with a controller or arm 97, which runs on a longitudinal rod 99, extending rearwardly from a 30 bracket 101 in the front of the machine. The movement of this slide 98 on the rod 99 when the carriage 53 is moved forward produces a frictional resistance, which acts to rock the clamp 96 on its pivot 100 and to clamp its edge with the edge of the plate 95. The instant the backward movement of the carriage 53 begins this frictional resistance acts in the opposite direction and opens the clamp 96. Thus while the carriage 53 is moving forward 40 the edges of the plate 95 and clamp 96 are clamped together; but at the moment when the carriage 53 starts to move back they are unclamped.

I have shown the controller or arm 97 provided with a shoe 98, running upon the bar 99. In the drawings this shoe is shown consisting of a longitudinally-divided tubular sleeve embracing the bar 99, with one half carried by the arm 97 and the other half connected therewith by pins 102, with springs 103 interposed between the pins and the sleeve-section, thus uniting the sections of the sleeve 98 by a yielding connection.

The bottom-formers 60 61 are carried by 55 the pedestal 53 and consist of suction-formers having perforated faces adapted to move apart as the carriage reciprocates and to break down the end of the paper-tube, which adheres to their suction-faces, into the desired 60 folds.

62 62^a are cheek-plates or extensions carried by the pedestal 53, one on each side, to which the movable suction-formers are hinged. Instead of using formers composed 65 of independent sections hinged together, as in the patents referred to, I employ collapsing sections so constructed that as the sec-

tions vary their angular relations one section will collapse upon the other at the back, each section being moved on a transverse axis at 70 its rear. The suction-former 60 is hinged to the plate 62 at one end on a pivot 104, and in the construction shown consists of two hollow boxes or sections 63 64, of which the outer box or section 64 fits within the side plates 75 136 136 of the section 63 (see Fig. 7) and is hinged to the end frame 65 through an arm 66, connected with the frame 65 by a pivot 67. The sections 63 64 are provided with perforated suction-faces 68 69, and the back 105 of 80 the inner section 63 is curved and fits over the curved back 106 of the section 64, so that either section may move with reference to the other on its respective pivot 104 or 67. The lower suction-former 61 is identical in construction and arrangement with the suction-former 60, consisting of an inner section 63^a, having a perforated face 68^a and pivoted at 104^a to the opposite side cheek 62^a, and an outer section 64^a, having a perforated face 9c 69^a and hinged at 67^a, through an arm 66^a, to the end frame 65^a of the section 63^a, the curved back 105^a of the section 63^a fitting over the curved back 106^a of the section 64^a and permitting the two sections to move with respect 95 to one another on their respective pivots or axes.

To avoid the use of means for independently creating a suction in each section, the sections 63 64 and 63^a 64^a, respectively, communicate with one another, so that it is necessary to connect the suction-creating devices with one section only. In the construction shown this is readily permitted by the feature of the collapsibility of the sections at 105 the back, the rear of the front sections 64 64^a opening into the front of the rear sections 63 63^a. Other means may, however, be employed for establishing this communication without using the collapsible sections. 110

As the carriage 50 reciprocates the formers 60 61 are moved apart, and the angular relations of their sections are varied. Suitable mechanism may be employed for this purpose, such, e. g., as is shown in the patents of Purvis referred to. I have, however, shown a special form of mechanism for operating the sections, which I shall now describe; but it is to be understood that the same forms no part of the present invention, as it is the subject-matter of an application for Letters Patent of Richard Max Uhlmann, Serial No. 686,564, filed July 22, 1898. These devices are as follows: 107 is a gear-wheel on the pivot 104 of the end frame 65 of the section 63. 108 115 is a gear-wheel carried on a stud 109, journaled in the side cheek 62 and carrying an arm 110, on the end of which is a roller 111. 112 is a gear-wheel carried by the pivot 67 of the arm 66 of the outer section 64, and 113 is 125 an intermediate gear on the frame 65, between the gears 107 and 112. 114 is a roller on an arm 115, carried by the end frame 65 of the section 63. Similar devices are employed at

the opposite side for operating the sections 63^a 64^a. 107^a is the gear-wheel on the pivot 104^a. 108^a is the gear-wheel carried by a stud 109^a, journaled in the side cheek 62^a, and 5 carries the arm 110^a, provided on its end with the roller 111^a. 112^a is the gear-wheel carried by the pivot 67^a of the arm 66^a of the section 64^a. 113^a is the intermediate gear between the gears 107^a and 112^a, and 115^a is the 10 arm on the end frame 65^a, which carries the roller 114^a.

116 116^a are cams (shown as cam-slots) on which the rollers 111 and 114 and 111^a and 114^a, respectively, run and by which the formers 60 61 are moved apart and the angular relations of their sections are varied. As 15 shown, these cam-slots are formed in plates 117 117^a, located one on each side of the machine. The cam-slot 116, which operates the upper former 60, has a lower portion 118, an upper portion 119, and an intermediate upwardly-inclined connecting portion 120, (see Fig. 1,) while the cam-slot 116^a, which operates the lower former 61, is oppositely arranged, having an upper portion 118^a, a lower portion 119^a, and an intermediate downwardly-inclined connecting portion 120^a. (See Fig. 3.)

When the carrier 50 is in its rearmost position, as shown in Fig. 3, the rollers 111 and 30 111^a are in the rear ends of the slot portions 118 118^a, and the rollers 114 114^a are in the front ends thereof, adjacent to the inclined portions 120 120^a. As the carrier 50 moves forward the rollers 114 114^a move in the inclined portions 35 120 120^a and rock the inner sections 63 63^a on their pivots 104 104^a through approximately ninety degrees, or until they are brought into substantially a vertical plane with reference to one another, as shown in Fig. 19. 40 During this portion of the movement of the carrier 50 the angular position of the outer sections 64 64^a is not changed, as the rollers 111 111^a, which operate them, are traveling over the horizontal portions 118 118^a of the 45 cams. At this moment, therefore, the sections 64 64^a occupy a substantially rectangular position with reference to the sections 63 63^a, as shown in Fig. 19; but as the carrier 50 continues in its forward movement the 50 rollers 114 114^a move forward over the cam portions 119 119^a without affecting the angular positions of the sections 63 63^a, while the rollers 111 111^a travel on the inclined portions 120 120^a and rock the outer sections 64 64^a on 55 their pivots 67 67^a through the gears 108, 107, 113, and 112, and 108^a, 107^a, 113^a, and 112^a, until they are opened out into a substantially vertical position in the same plane with the sections 63 63^a, as shown in Fig. 6. On the 60 return of the carrier 50 these motions are reversed. In Fig. 18 the sections are shown in an intermediate position before the inner sections 63 63^a are moved fully open. The tube-section, which is fed to the carrier in the condition shown in Fig. 22, with its end lying between the suction-formers, is first brought into the partially-opened position shown in

Fig. 23, when the formers assume the positions shown in Fig. 18, is then brought into the condition shown in Fig. 24, when the formers 70 are in the positions shown in Fig. 19, and is finally flattened out into the condition shown in Fig. 25, when the sections are fully opened, as shown in Fig. 6.

To avoid the use of flexible tubes communicating with the formers 60 61, as in the patents referred to, I create the suction through passage-ways in the framework communicating with the formers through their journals 104 104^a. 75

121 is a tube or passage-way leading from the fan or suction-creating device (not shown) and opening through the base-plate 51 into a chamber 122 therein (see Fig. 15) which communicates through a guideway 52 with a longitudinal slot 123 in the base of the reciprocating carrier 50, whereby communication between the base of the carrier and the suction passage-way 121 is maintained. 85

The base 50 is hollow and communicates 90 with the interior 125 of the hollow pedestal 53, which through side openings 126 126^a communicates with passage-ways 127 127^a through the extensions or side cheeks 62 62^a, leading through the journals 104 104^a to the interior 95 of the formers 60 61. (See Fig. 29 and dotted lines in Fig. 5.)

To control the suction in the formers and positively interrupt it to release the tube-section at the proper moment, a valve or damper 100 246 in the flue 121 may be employed. This is shown operated by a lever 247, connected at one end with the valve or damper by a link 248 and at the other end with the crank 57 by a link 249. (See Figs. 1 and 4.) 105

To assist the suction in breaking the paper into the square-box shape shown in Fig. 24 and to aid in the formation of the usual diamond side folds, former-fingers have been used projected into the diamond folds while 110 the bottom is being formed. To insure the positive projection and retraction of these fingers at the proper intervals and to simplify their operation, I arrange the fingers movably upon one of the sections of the former 115 and employ means carried by the other section for operating them.

As shown, these devices are as follows: 120 137 137 and 137^a 137^a are the folder-fingers, located one on each side of each section 63 63^a and adapted at a certain moment to be projected forward over the paper into the diamond side folds forming therein. The fingers 137 137 are each carried by a slide 138, guided longitudinally in the top 105 of the 125 section 63, and the fingers 137^a 137^a are similarly carried each by a slide 138^a, guided longitudinally in the top 105^a of the section 63^a. Pins or lugs 139 139 on these slides 138 engage cam slots or grooves 140 140 in an arm 130 141, carried by the outer section 64, and similar pins or lugs 139^a 139^a on the slides 138^a engage similar cam slots or grooves in an arm 141^a, carried by the section 64^a. As the in-

ner sections 63 63^a are rocked on their pivots 104 104^a their tops 105 105^a are moved under the arms 141 141^a of the sections 64 64^a, and the cam-slots 140 140^a act upon the lugs or 5 projections 139 139^a and draw the slides 138 138^a inward, thus moving the fingers inwardly over the paper upon the faces of the suction-formers at the time the inner sections 64 64^a are moving upwardly to break the bottom of 10 the bag into the square-box shape and form the diamond side folds. Upon the upward movement of the sections 64 64^a upon their pivots 67 67^a the cam-slots 140 140^a act upon the pins 139 139^a in the opposite direction, 15 and thus retract the fingers 137 137^a.

128 128^a are plates arranged transversely to the planes of the faces of the former-sections, one on each side, and are adapted when the former-sections assume the rectangular 20 position, which breaks the bottom of the bag-section into the square-box shape, to occupy positions immediately adjacent to the opened sides of the formers and to be projected forward so as to press slightly upon the sides of 25 the paper and thus insure the formation of the square-box folds.

In the construction shown the plates 128 128^a are carried on the ends of short rods 129 129^a, carried in suitable guides in frames 130 130^a on the side cheeks 65 65^a of the former-sections 63 63^a, and are normally retracted 30 by springs 131 131^a. 132 132^a are arms carried by the rods 129 129^a (shown projecting laterally through longitudinal slots 133 133^a 35 in the guides) and provided on their ends with rollers 134 134^a, adapted to be acted upon by cams 135 135^a, Fig. 2, when the carrier 50 reciprocates. The operation of these devices is as follows: When on the forward movement 40 of the carriage 50 the sections 63 63^a are rocked on their pivots 104 104^a by the action of the cams 120 120^a on the roller 114 114^a, as heretofore described, the frames 130 130^a and the plates 128 128^a, which they carry, are 45 moved with them, so as to occupy a position immediately adjacent to and in advance of the faces 68 68^a of the sections 63 63^a, as shown in Fig. 6, the frame 130 and its plate 128 moving upward and the frame 130^a and its plate 50 128^a moving downward. At this moment the outer sections 64 64^a occupy a position substantially at right angles to the sections 63 63^a, and the paper which adheres to their perforated faces is opened out into a square-box shape, 55 and the rollers 134 134^a are acted upon by the cams 135 135^a, and the plates are projected inward to a slight extent into the side openings between the former-sections. These plates press upon the sides of the paper and act to 60 straighten it out and more perfectly break it into the square-box shape.

When the formers reach the end of their forward reciprocation with the sections thereof opened up, as shown in Fig. 6, and the bottom of the tube folded, as shown in Fig. 25, flattening-plates are folded down upon the opened faces of the formers to flatten out the

bottom of the bag. These plates may be operated in any convenient manner—e. g., as shown in the Purvis patent, No. 578,361. I have shown special devices for this purpose, which, however, form no part of the present invention, as they are a part of the subject-matter of the application of Richard Max Uhlmann, Serial No. 686,564, before referred to. As shown, these devices are as follows, Figs. 2 and 3: 142 142 are plates hinged on vertical axes to arms 143 on rods 144 144, guided in a transverse frame 145 in the front of the machine and connected at the rear with a bar 80 146, operated by arms 147 147 of a rock-shaft 148, journaled in the brackets 101. 149 is a rod hinged to one of the arms 147 and extending rearwardly over the suction-formers and guided at the rear in a guide 184. 185 is a 85 stop (shown adjustable) carried by the rod 149 adjacent to the rear thereof. 186 is a guide or jaw carried by the frame 65^a of the suction-former 60, engaging the rod 149 and adapted at the end of the backward movement of the former 60 to strike the stop 185 and impart a slight backward movement to the rod 149, thus rocking the shaft 148 and projecting the rods 144 144. 191 is a yielding frame having an extension 187, guided in the frame 145, and provided with arms 188, acting as yielding bearings for the plates 142 142 adjacent to their hinge-points. 189 is a spring normally pressing the frame 191 forward and permitting it to yield. 190 190 are 100 springs normally retracting the plates and maintaining them in contact with the arms 188 188, as shown in Fig. 2. At the end of the forward movement of the formers 60 61 (which are then opened up, as shown in Fig. 105 6) they strike the outer edges of the plates 142 142 and press the yielding rods 144 back, rocking the plates upon their hinges about the arms 188 as fulera and folding the plates positively down upon the face of the paper. On the backward movement of the formers the jaw 186 strikes the stop 185 and moves 110 back the rod, (which has been moved forward by the movement of the rods 144,) restoring the plates to the positions shown in 115 Fig. 2.

The final-folding and pasting devices, (Figs. 3, 3^a, 10, 13, and 16.)—The stripping-cylinder 150 is located immediately in front of the reciprocating formers 60 61 in position to receive the bag-section therefrom when the formers reach the limit of their forward movement and is provided with a gripper 151, operated by a cam 152 to seize the flap on the lower portion of the bottom and remove the 120 bag-section from the formers.

To insure a positive, certain, and elastic gripping action in the gripper 151, I employ a yielding connection between the gripper or gripper-shaft and the part actuated by the 130 cam 152. This construction is particularly shown in Figs. 36 and 37. The gripper 151 is secured to a shaft 252, journaled longitudinally in the cylinder 150.

253 is the arm, which is rocked by the cam 152 and carries the usual roller 254. This arm is yieldingly connected with the gripper-shaft 252 by a strong spring 255, through 5 which the gripper-shaft and gripper are actuated when the arm is moved by the cam, but which permits the arm to move independently of the gripper-shaft after the gripper is clamped upon the paper. In the particular construction shown the arm 253 is carried by a short sleeve 256, encircling the shaft 252 and connected by a coiled spring 255 with an enlargement 257 on the gripper-shaft. By these means the difficulty of properly shaping and adjusting the cam to insure a certain gripping action is entirely avoided and the cam is made of a size sufficient to impart slightly more movement to the arm than is necessary to close the gripper. As 10 the gripper is actuated through the spring, it acts elastically upon the paper without liability of injuring it.

153 is a feed-roller located below the stripping-roller 150 and running in contact with the periphery thereof, between which and the roller 150 the bag-section is fed.

154 is a pasting-roller provided with the usual pasting-form, which receives paste from the usual rollers 155 156 and applies it to the 20 bag-bottom.

157 is the usual roller running in contact with the pasting-roller, between which and the pasting-roller the bag passes while the paste is being applied to its bottom.

35 158 is an intermediate guiding-roller between the rollers 153 and 157, over which the bag-section is guided when released by the gripper 151.

159 160 are the first pair of rollers over which 40 the bag passes when delivered from the pasting-rollers 154 157 and between which it passes when the first final fold is formed.

161 162 is the second pair of rollers over which the bag passes when delivered by the 45 rollers 159 160 and between which it passes when the second final fold is formed.

163 is the guide-plate extending over the roller 160 for guiding the end of the bag-section to permit the first final fold to be formed, 50 and 164 is the guide-plate projecting over the roller 162 for guiding the end of the bag-section to permit the second final fold to be formed.

165 and 166 are respectively the reciprocating tuckers or plates adapted to reciprocate, 55 respectively, between the rollers 159 160 and 161 162 to form the final folds.

The bag-section when delivered from the formers is carried bottom foremost between 60 the rollers 150 153, being flattened thereby into the condition shown in Fig. 26, and passes over the roller 158, between the rollers 154 157, where paste is applied to its bottom in the usual manner. Thence it passes over the rollers 159 160, under the tucker-plate 165, (which is then in the position shown in Fig. 3^b), with its forward end resting on the plate 163. The

plate 165 descends, forming the first final fold, as shown in Fig. 27, and directing the bag-section between the rollers 159 160, whence 70 it descends under the tucker-plate 166, (which is then in the position shown in Fig. 3.) with its front end under the plate 164, which prevents the first fold from reopening. The tucker-plate 166 then rocks, acting upon the 75 unfolded end and folding it up upon the bottom, as indicated in Fig. 28, and directing the bag-section between the rollers 161 162, from which the completed bag is discharged.

I shall now describe the apparatus for operating the tucker-plates 165 166, which is illustrated particularly in Figs. 10, 11, 12, 13, and 16.

167 168 are arms journaled on the shaft 169 of the roller 159, carrying a cross-bar 168, to 85 which the tucker-plate 165 is secured.

170 170 are projections of the arms 167 168 forming stops against the shaft 171 of the roller 160 to limit the descent when the plate is lowered to act on the bag-bottom.

172 is a movable (trip shown as a transversely-inovable slide) carried by the roller 159 and adapted to project at either end beyond the periphery thereof. This slide is provided on its end with lateral lugs or projections 173 174, projecting from the face thereof.

175 is a cam on the shaft 171, provided with a high projection 176 and a low projection 177, adapted to operate on the ends of the trip 172 and actuate it.

179 is a lug or lateral projection carried by one of the arms 167 and adapted to be actuated by the lugs 173 174 of the trip 172. The plate 166 is similarly carried by arms 167 167^a, journaled on the shaft 180 of the roller 161, and carrying a cross-bar 168^a, by which the plate 166 is carried. 170^a 170^a are stop projections of the arms 167^a 167^a, adapted to be arrested by the shaft 181 of the roller 162 when the plate 166 is lowered.

172^a is the trip on the roller 161, having the laterally-projecting lugs 173^a 174^a on its ends. 175^a is the cam on the shaft 181, having the high projection 176^a and the low projection 177^a, and 179^a is the lug or projection carried by one of the arms 167^a adjacent to the slide 172^a.

182 is a segmental gear carried by the journal of the arms 167 on the shaft 169 of the roller 159, adapted to engage a similar gear 120 183, carried by the journal of the arms 167^a on the shaft 180 of the roller 161. These gears 182 and 183 are so arranged that when one of the plates 165 166 is elevated the other is lowered, and vice versa. In the position shown in Figs. 10 and 11 the plate 165 is lowered and the plate 166 is raised. Considering the mechanism to occupy the positions shown in these figures, the operation is as follows: The high part 176^a of the cam 175^a is immediately adjacent to the end of the trip 172^a, and as the rollers 161 162 rotate it will strike the end of the trip 172^a and force it inward, projecting the opposite end outward to

the full extent, and when upon the rotation of the roller 161 this end of the trip reaches the projection 179^a of the rocking frame 167^a its lug 173^a will act thereon to depress it, thus rocking the plate 166 and causing it to act upon the bag-bottom and crease it and direct the bag between the rollers 161 162, as indicated in Fig. 28. This movement of the rocking frame 167^a will through the segmental

10 gears 182 183 rock the frames 167 167 and elevate the plate 165, as shown in Fig. 3^b. During these movements there has been no operation of the trip 172 of the roller 159, because the slide occupied an intermediate position with neither end fully projected. Immediately after the operation of the projected

15 trip 172^a upon the frame 167^a its end is struck by the low projection 177^a of the cam 175^a, thus restoring it to an intermediate position.

20 The high projection 176 of the cam 175 then strikes the end of the trip 172 and projects its opposite end in a similar manner, so that as the roller 159 rotates the lug 173 on the projected end of the trip will strike the projection 179 and depress the frames 167 and plate 165 and cause it to act upon the bag to crease it and direct it between the rollers 159 160, as shown in Fig. 27. At the same time

25 the frames 167^a and the plate 166 are elevated by the action of the segmental gears 182 183. Immediately after the trip 172 has thus acted upon the frame 167 it is struck by the low projection 178 and restored to intermediate position. This intermittent operation of the trips 172 172^a enables the rollers 159 160 and 30 161 162 to make more than a single revolution between each operation of the tucker-plates, so that the rollers may conduct the folded bag between them before the next

35 folding operation takes place. It will be observed that the tucker-plates are oscillated on axes concentric with the rollers.

The printing devices.—It is desirable in a machine of this character that devices should 40 be employed for printing upon the bags figures or symbols to indicate the size or capacity thereof. For this purpose a printing attachment is employed for printing the desired impression on each bag-section. As these 45 printing devices should operate to make impressions at exactly the same position on each bag, it is desirable that their time of action should be varied with any change in the length of the bag-sections to make the impressions 50 at greater or less intervals apart. It is also desirable to prevent blurring of the impressions that their speed of operation should be uniform with the speed of movement of the paper. For these purposes I employ means

55 for interrupting the operation of the printing devices and control their speed of operation through power-transmitting connections with the tube-feeding or drawing-in devices, so that whatever may be the speed of movement 60 of the paper the printing devices will operate uniformly therewith, while their intervals of action may be varied to suit the length of the

bag-sections. These devices are particularly shown in Figs. 1, 3^a, and 17. 178 is a type-cylinder arranged immediately adjacent to 70 the guide-roller 7, over which the paper passes as it travels to the tube-former and which acts as an impression-roller. The type-cylinder may be provided with a removable type-plate to provide for printing different sizes of 75 bags.

172 is an inking-roller for supplying ink from a fountain 193 to the type-cylinder 178. Power is imparted to the inking-cylinder and type-cylinder from a gear 194 through gears 80 195 196 on their respective shafts and an intermediate gear 203.

The type-cylinder is driven from a part of the machine which controls or is controlled by the speed of movement of the paper and 85 operates uniformly therewith. In the drawings it is shown driven from the drawing-in roller 26 through power-transmitting connections 239 240, of which 239 is a chain transmitting power from a sprocket-wheel 241 on 90 the shaft 47 to a sprocket-wheel 242 on a counter-shaft 243, and 240 is a belt transmitting power from a pulley 244 on the shaft 243 to a pulley 245 on the shaft of the pinion 194, and it is apparent that when the speed of the 95 drawing-in rollers 25 26 is accelerated or retarded to draw in the paper faster or slower the speed of the printing-cylinder will be correspondingly increased or decreased.

To control the time of impressions independently of the speed of the printing devices, I employ means for interrupting the operation of the printing devices at intervals. As shown, these devices are as follows: The impression-cylinder has a yielding or frictional 100 connection with its gear 196 through a spring 197, and a stop 198, carried by the type-cylinder, is acted upon by a reciprocating rod 199, controlled by the driving devices of the machine, to interrupt the action of the type-cylinder at intervals of greater or less length, according to the size of the bag being made. This rod 199 is carried by an eccentric 200 on the shaft 32, and its outer end is guided in a 105 guide 201 and arranged to be projected into 110 the path of the stop 198 to temporarily arrest the type-cylinder and control its operation.

The driving devices.—Power may be distributed to the various operative parts of the machine in any suitable manner. The devices which are shown are as follows: From the shaft 3 motion is imparted, through the gear 206 thereon, to the counter-shaft 58 (by which the former carriage 50 is reciprocated, as has been described) through a gear-wheel 120 207, carried by said counter-shaft.

208 is a pinion on the shaft 3, through which the counter-shaft 81, which drives the cutter-bar 45, is driven through gears 209 210.

The counter-shaft 32, which carries the eccentric 200 and the cam 36 for controlling the printing devices and slitters, respectively, is driven through a gear 213 thereon from the gear 210.

Power is imparted to the drawing-in rollers 25 26 from the shaft 32 by the gear-wheels 202 and 215 on the shafts 32 and 47, respectively, and an intermediate gear 204. By changing the gear 202 on the shaft 32 and adjusting the intermediate gear 204 by the adjustable arm or lever 216, which carries it, the speed of the drawing-in rollers 25 and 26 may be accelerated or retarded to increase or decrease the speed with which the paper travels.

The feed-rollers 82 83 are driven from the gear 215 through a gear 214 on the shaft 85 of the roller 83 and an intermediate gear 217. The feed-rollers 89 and 90 are driven from the gear 214 through the gear 94 on the shaft 93 and an intermediate gear 218.

The final-folding and pasting devices are driven from the shaft 58 through a chain 219 and sprocket-wheels 220 and 221, respectively, on the shaft 58 and the shaft 222 of the roller 158.

The gripping-roller 150 and the pasting-roller 154 are driven from the gear 223 on the shaft 222 through gears 224 and 225 on their respective shafts. The rollers 153 and 157 are driven from the gears 224 and 225, respectively, through gears 236 and 237 on their respective shaft. The paste-feeding rolls are driven from the gear 225 through gears 226 227.

The rollers 159 and 160 are geared together by gears 231 232 and are driven by a gear 228 on the shaft of the roller 159 from the gear 223 through an intermediate gear 230. The rollers 161 162 are similarly geared together by gears 233 234 and are driven from the gear 230 through a gear 229 on the shaft of the roller 161.

It will thus be seen that the machine embodies two systems of driving—the direct system from the power-shaft 3, which drives the striker-bar 45, the reciprocating bottom-formers, the final-folding and pasting devices, and the shaft 32 with a constant uniform movement, and the indirect or variable system controlled by the change-gear 202, which drives the drawing-in and tube-feeding devices, the slitters, and the printing devices with a variable movement. This method of driving permits the adjustment of the machine to the making of bags of different sizes. To make such an adjustment, the cam-plates 117 117^a, which are adjustably secured to the side frames 1 1, as by slotted arms and set-screws 260, are loosened to permit the arms 111 114 111^a 114^a to be disengaged from the slots in the plates 117 117^a, the pedestal 53 is detached from the carriage 50, and the end frame 145 with the brackets 101 is detached from the plates 117 117. The formers with the pedestal 53 and the frame 145 with the flattening-plates 142 and the rods 99 and 149 are removed and corresponding parts of a different size are substituted for them; the cam-plates 117 117 being suitably adjusted to receive them. The tube-former is detached

from the pendant 12, which supports it, and removed, together with its folding-fingers, and a new tube-former of proper size is substituted. The gear 202 is changed to increase or decrease the speed of the paper to suit the longer or shorter length of the tube-sections to be formed, and the segment 36 and eccentric 200 are adjusted on the shaft 32 to correspondingly regulate the timing of the action of the slitters and printing devices.

While I have shown my improved tube-forming devices, slitters, printing devices, and final-folding and pasting devices combined with the reciprocating suction-formers, it is understood that they may be used with other bottom-forming devices and that my improvements in the bottom-forming devices may be employed in combination with other forms of tube-formers, slitters, printing devices, and final-folding or pasting devices.

The various details of construction which have been shown may be varied without departing from the invention.

What I claim as new, and desire to secure by Letters Patent, is as follows:

1. In a paper-bag machine, the combination of bottom-forming devices for forming the bottom of a paper-tube section, tube-forming devices, drawing-in and tube-feeding devices for drawing the paper through the tube-former and feeding the tube-section to the bottom-forming devices, printing devices for printing impressions on the paper tube, a cutter for cutting the tube into bag-sections, power devices for driving the bottom-forming devices at a uniform speed, power devices for driving the drawing-in and tube-feeding devices, and the printing devices at a relatively uniform speed, and means for varying the speed of the drawing-in and tube-feeding and printing devices relatively to the bottom-forming devices.

2. In a paper-bag machine, a bellows-side-fold-tube-forming device, consisting of a plate over which the edges of the paper are folded, a plate in contact with and around the edges of which the paper is drawn, terminating at the rear in an inclined extension, an outwardly-inclined guiding finger or extension projecting out from the rear of the first-mentioned plate above said inclined extension, and the folders for folding down the edges of the paper and forming the bellows folds in the side thereof.

3. In a paper-machine, the tube-forming devices, consisting of a plate over which the edges of the paper are folded, the folding-fingers for folding said edges, and a second plate in contact with and around the edges of which the paper is drawn terminating at the rear in an inclined extension having outwardly-inclined side edges and forming a transverse angle with the rear of said second plate, the surface of said second plate over which the paper passes inclining gradually forward from said transverse angle toward the first plate.

clamp-controller carried by said clamp, a friction-bar and a friction-creating device carried by said controller and acting on the friction-bar to operate the controller by frictional resistance and close the clamp on the forward movement of the carrier.

18. In a paper-bag machine, a reciprocating carrier, suction-formers for forming the end of the paper tube as the carrier reciprocates, a movable clamp carried by said carrier and adapted to clamp and release the paper, a clamp-controller carried by said clamp, a bar 99, and a shoe 98 engaging said bar and adapted to operate the controller to close and open the clamp, while the carrier is reciprocating, by the friction of said shoe upon the bar.

19. In a paper-bag machine, suction bottom-formers composed of hollow sections, the back of one section extending over the back of the other section and collapsing thereon when the sections are moved.

20. In a paper-bag machine, suction bottom-formers composed of hollow collapsing sections communicating with one another internally.

21. In a paper-bag machine, the suction bottom-former, composed of two hollow sections communicating with one another at the interior, the rear of one section engaging the front of the other and guided thereon when the angular relations of said sections are varied.

22. In a paper-bag machine, a suction bottom-former composed of two hollow sections communicating with one another internally.

23. In a paper-bag machine, a suction bottom-former composed of two hollow sections communicating with one another internally in combination with a reciprocating carrier carrying said former and provided with a suction passage-way communicating with the interior thereof.

24. In a paper-bag machine, a suction bottom-former composed of two hollow sections communicating with one another internally, in combination with a reciprocating carrier carrying said former and provided with a suction passage-way communicating with the interior thereof, and a frame, on which said carriage is reciprocated, having a suction passage-way communicating with the passage-way of said carriage.

25. In a paper-bag machine, the combination of the frame having a suction passage-way terminating in an extended opening, a reciprocating carriage guided on said frame, and having a passage-way provided with an opening in communication with the extended opening in the frame, and a hollow suction-former carried by said carriage and communicating with the passage-way therein.

26. In a paper-bag machine, the combination of a hollow suction-former for forming the end of a paper tube, and a reciprocating carriage carrying said former and provided with a passage-way communicating with the interior thereof.

27. In a paper-bag machine, the suction-

former consisting of two hollow sections communicating with one another internally and provided with perforated suction-faces, the back of the outer section extending within the front of the inner section, and each section being movable on a transverse axis at its rear.

28. In a paper-bag machine, the combination of a reciprocating carriage, suction-formers hinged thereto and each consisting of two hollow sections, communicating with one another internally, and means to move said formers apart and change their angular relation as the carriage reciprocates.

29. In a paper-bag machine, the combination of a reciprocating carriage, suction-formers hinged thereto and each consisting of two hollow sections, communicating with one another internally and adapted to collapse upon one another, and means to move said formers apart and change their angular relation and collapse their sections as the carriage reciprocates.

30. In a paper-bag machine, the combination with a suction-former composed of sections adapted to vary their angular relations, of movable former-fingers carried by one section, and means carried by the other section for operating said former-fingers and projecting them upon the face of one of the sections when the angular relations of the said sections are varied.

31. In a paper-bag machine, the combination with the suction-former composed of two sections adapted to collapse upon one another at the back, of movable former-fingers carried by one section, and means carried by the other section and adapted to act upon said movable former-fingers and project them upon the face of one of said sections when said sections are collapsed upon one another.

32. In a paper-bag machine, the combination with the suction-former composed of two sections adapted to vary their angular relations, of slides carried by one of said sections, former-fingers carried by said slides and adapted to be projected upon the face of said former-section, and means carried by the other former-section to operate said slides and project and retract the former-fingers at certain moments during the angular movements of the sections.

33. In a paper-bag machine, the combination with the suction-former composed of sections adapted to vary their angular relations, of slides carried by one of said sections, an arm carried by the other section and provided with cam-slots engaging said slides and adapted to reciprocate them during the angular movements of the former-sections, and former-fingers located adjacent to the face of the suction-former and carried by said slides and adapted to be projected and retracted by the reciprocations thereof.

34. In a paper-bag machine, the combination with suction-formers for opening up the bottom of a paper tube into a square-box shape, of reciprocating plates located at the

4. In a paper-bag machine, the combination of drawing-in rollers, tube-forming devices, rotating slitters for forming slits at intervals in the paper tube, and means for arresting and suspending the rotation of said slitters at intervals. 70
5. In a paper-bag machine, the combination of drawing-in rollers, tube-forming devices, rotating slitters for forming slits at intervals in the paper tube, power-transmitting connections for operating said slitters at a speed relatively uniform with the drawing-in rollers, and means for arresting and suspending the rotation of said slitters at intervals. 75
- 10 6. In a paper-bag machine, the combination of drawing-in rollers, tube-forming devices, slitters for forming slits at intervals in the paper tube, power-transmitting connections for operating said slitters at a speed relatively uniform with the drawing-in rollers, means for accelerating or retarding the speed of the drawing-in rollers, and means for interrupting the movement of said slitters at intervals. 80
- 15 7. In a paper-bag machine, the slitting devices for forming slits at intervals in the moving tube, consisting of the rotating knives 28, 28, driving devices therefor, a yielding connection between said knives and their driving devices, and means to interrupt the rotation of said knives at intervals. 85
- 20 8. In a paper-bag machine, the slitting devices for forming slits at intervals in the moving tube, consisting of the rotating knives 28, 28, driving devices therefor, a yielding connection between said knives and their driving devices, and means to interrupt the rotation of said knives at intervals, consisting of a rotating cam 42, and a finger 35 carried 90 with the knives and adapted to be arrested by the cam. 95
- 25 9. In a paper-bag machine, the combination with feeding devices for feeding the tube, slitters for slitting the tube at intervals, printing devices for printing impressions on the tube at intervals, driving devices for operating said slitters and printing devices, means for interrupting the movement of said slitters, and means for interrupting the movement of 100 said printing devices. 105
- 30 10. In a paper-bag machine, the combination with feeding devices for feeding the tube, means for accelerating or retarding the operation of said feeding devices, slitters for slitting the tube at intervals, printing devices for printing impressions on the tube at intervals, and driving devices for operating said slitters and printing devices at speeds relatively uniform with said feeding devices. 110
- 35 11. In a paper-bag machine, the combination with feeding devices for feeding the paper tube, slitters for cutting slits therein at intervals, driving devices for operating said slitters at a speed relatively uniform with the feeding devices, means for accelerating or retarding the speed of said feeding devices, and means operated independently of said means 115 for accelerating or retarding the speed of said feeding devices, for interrupting the movement of said slitters at intervals. 120
- 40 12. In a paper-bag machine, the combination with devices for feeding the paper, of a rotary slitter having a circumferential speed uniform with the speed of the paper, and means to temporarily interrupt the rotation of said slitter at intervals. 125
- 45 13. In a paper-bag machine, the combination of tube-feeding devices, a counter-shaft, slitters for forming slits in the paper tube at intervals, a power-shaft, power-transmitting connections between said power-shaft and counter-shaft, driving connections between said counter-shaft and tube-feeding devices having provision for accelerating or retarding the speed thereof with reference to the counter-shaft, driving connections between the feeding-rollers and the slitters, and means for interrupting the movement of said slitters controlled by said counter-shaft. 130
- 50 14. In a paper-bag machine, the combination of tube-feeding devices, a counter-shaft, a cutter-bar, driving connections between said counter-shaft and cutter-bar, slitters for forming slits in the paper tube at intervals, a power-shaft, power-transmitting connections between said counter-shaft and power-shaft, driving connections between said counter-shaft and tube-feeding devices having provision for accelerating or retarding the speed thereof with reference to the counter-shaft, driving connections between the feeding-rollers and the slitters, and means for interrupting the movement of said slitters controlled by said counter-shaft. 135
- 55 15. In a paper-bag machine, the combination of tube-forming devices, drawing-in rollers for drawing in the paper over said tube-forming devices, a stationary cutter over which said tube is fed, a moving cutter-bar, driving devices for operating said cutter-bar at a uniform speed, and means for accelerating or retarding the speed of the drawing-in rollers independently of the speed of operation of said cutter-bar, slitters for slitting said tube at intervals, and power-transmitting connections for operating said slitters at a speed relatively uniform with the drawing-in rollers. 140
- 60 16. In a paper-bag machine, a reciprocating carrier, suction-formers for forming the end of the paper tube as the carrier reciprocates, a clamp carried by said carrier for clamping the paper tube while its end is being formed by said formers and releasing it after its end has been formed, a clamp-controller for closing said clamp on the forward movement of the carrier and releasing it at the end of said movement, and means acting on said controller during the reciprocations of the carrier to actuate it. 145
- 65 17. In a paper-bag machine, a reciprocating carrier, suction-formers for forming the end of the paper tube as the carrier reciprocates, a movable clamp carried by said carrier and adapted to clamp and release the paper, a 150

sides in transverse planes to the suction-faces of said formers and adapted to be projected against the sides of the paper tube when opened up into the square-box shape.

5 35. In a paper-bag machine, the combination with reciprocating suction-formers for opening up the bottom of a paper tube into a square-box shape, of reciprocating plates carried with said formers and located at the sides 10 in transverse planes to the suction-faces thereof, and means to project said plates against the sides of the paper tube when opened up into the square-box shape.

36. In a paper-bag machine, the combination with the suction-formers composed of sections adapted to move apart and vary their angular relations, of the plates 128, 128^a arranged transversely to the sides of the suction-formers and adapted to be projected forward against the sides of the paper tube when it is opened up by the movement of the suction-formers.

37. In a paper-bag machine, the combination with the suction-formers composed of sections 63, 64, 63^a, 64^a, adapted to move apart and vary the angular relations of their sections, of the plates 128, 128^a arranged transversely to the sides of the suction-formers, and carried respectively by the inner sections 30 63, 63^a and adapted to be projected when the suction-formers are partially opened up and said sections 63, 63^a occupy substantially the same plane with one another.

38. In a paper-bag machine, the combination with reciprocating suction-formers composed of sections 63, 64, 63^a, 64^a, adapted to move apart and vary the angular relations of their sections as the formers reciprocate, of the plates 128, 128^a arranged transversely to 40 the sides of the suction-formers, rods carrying the plates and supported by the inner sections 63, 63^a, and cams adapted to actuate said rods and project the plates at the sides between the opened formers as said formers are reciprocated.

39. In a paper-bag machine, the combination with reciprocating suction-formers composed of sections 63, 64, 63^a, 64^a, adapted to move apart and vary the angular relations of 50 their sections as the formers reciprocate, of the plates 128, 128^a arranged transversely to the sides of the suction-formers, rods carrying the plates and supported by the inner sections 63, 63^a, springs normally retracting said rods, and cams adapted to actuate said rods and project the plates at the sides between the opened formers as said formers are reciprocated.

40. In a paper-bag machine, the final-folding devices, consisting of two pairs of guide-rollers between which the paper tube is successively guided, reciprocating tucker-plates for directing the paper tube between said pairs of guide-rollers each hinged concentrically with one of the rollers in one pair, means for operating said tucker-plates alternately, and connections between said tucker-

plates whereby one is raised when the other is lowered and vice versa.

41. In a paper-bag machine, the final-folding devices, consisting of two pairs of guide-rollers between which the paper tube is successively guided, reciprocating tucker-plates for directing the paper tube between said pairs of guide-rollers, and a trip device for operating each of said tucker-plates.

42. In a paper-bag machine, the final-folding devices, consisting of two pairs of guide-rollers between which the paper tube is successively guided, reciprocating tucker-plates for directing the paper tube between said pairs of guide-rollers, a trip device for operating each of said tucker-plates, and connections between said tucker-plates whereby one is raised when the other is lowered and vice versa.

43. In a paper-bag machine, the final-folding devices, consisting of a pair of guide-rollers between which the paper tube is guided, a reciprocating tucker-plate for directing the paper tube between said pairs of guide-rollers, a trip for operating said tucker-plate, and means for throwing said trip into and out of operation.

44. In a paper-bag machine, the final-folding devices, consisting of a pair of guide-rollers between which the paper tube is guided, a reciprocating tucker-plate for directing the paper tube between said guide-rollers, a trip carried with one roller of the pair adapted when projected to operate the tucker-plate, a rotating cam for projecting the trip into operative position at certain intervals.

45. In a paper-bag machine, the final-folding devices, consisting of the pairs of rollers 159, 160 and 161, 162, the rocking tucker-plates 165, 166 for folding the bag-bottom and directing it between the rollers, connections between the tucker-plates whereby when one is raised the other is lowered and vice versa, the sliding trips 172, 172^a carried with the rollers 159 and 161 respectively, and the cams 175, 175^a provided with the high and low projections 176, 177, 176^a, 177^a respectively, substantially as and for the purposes described.

46. In a paper-bag machine, the combination with a pair of final-folding rollers, of a tucker-plate adapted to fold the end of the paper tube and direct it between the rollers, a trip carried with one roller for operating said tucker-plate, and a rotating cam for projecting said trip into operative position at certain intervals, and means for restoring said tucker-plate after it has been operated by said trip.

47. In a paper-bag machine, the combination with a pair of final-folding rollers, of a tucker-plate adapted to fold the end of the paper tube and direct it between the rollers, a trip carried with one roller for operating said tucker-plate, and a rotating cam for projecting said trip into operative position at certain intervals and provided with a small cam projection for restoring said trips into inop-

48. In a paper-bag machine, the combination with drawing-in rollers, and tube-forming devices, of means for accelerating or retarding the drawing-in rollers, printing devices for printing an impression at intervals upon the paper, driving devices for operating said printing devices, means for intermittently interrupting the movement of said printing devices, and power-transmitting connections between the drawing-in rollers and means for interrupting the action of the printing devices.
- 15 49. In a paper-bag machine, the combination with feeding-rollers and tube-forming devices, of a rotary type-cylinder for printing impressions on the paper, intermittently-operating stop devices for interrupting the rotation of said type-cylinder, and power-transmitting connections between the feeding-rollers and stop devices.
- 20 50. In a paper-bag machine, the combination with feeding-rollers for feeding the paper tube, of a rotary type-cylinder, a stop carried thereby, and a reciprocating rod adapted to be projected into the path of the stop to interrupt the rotation of the type-cylinder at intervals.
- 25 51. In a paper-bag machine, the combination with feeding-rollers for feeding the paper tube, of a rotary type-cylinder, driving devices for said type-cylinder having a yielding connection therewith, a stop carried by said type-cylinder, and a reciprocating rod adapted to be projected into the path of the stop to interrupt the rotation of the type-cylinder at intervals.
- 30 52. In a paper-bag machine, the combination with feeding-rollers for feeding the paper tube, of a rotary type-cylinder, driving devices for said type-cylinder having a yielding connection therewith, power-transmitting connections for operating said driving devices at a uniform speed with the feeding-rollers, means for accelerating or retarding the speed

of the feeding-rollers, a stop carried by said type-cylinder, a reciprocating rod adapted to be projected into the path of the stop to interrupt the rotation of the type-cylinder at intervals, and power-transmitting connections for operating said reciprocating rod at a uniform speed with the feeding-rollers.

55 53. In a paper-bag machine, the printing devices for printing impressions on the paper, consisting of the rotary type-cylinder 178, the driving devices having a yielding connection therewith, the stop 198 carried by the type-cylinder, and intermittently-operating means acting on said stop for interrupting the rotation of the type-cylinder at intervals.

60 54. In a paper-bag machine, the combination with feeding devices for feeding the paper tube, printing devices for printing impressions upon said tube, driving devices for operating said printing devices at a speed relatively uniform with the tube-feeding devices, means for accelerating or retarding the speed of said feeding devices, and means operated independently of said means for accelerating or retarding the speed of said feeding devices, for interrupting the operation of said printing devices at intervals.

65 55. In a paper-bag machine, the combination of feeding-rollers for feeding the paper tube, printing devices for printing impressions upon the paper at intervals, driving devices for operating said printing devices at a uniform speed with the feeding-rollers, intermittently-operating stop devices for interrupting the operation of said printing devices, having provision for adjustment to increase or decrease the period of interruption, and means for accelerating or retarding the speed of the feeding-rollers.

In testimony of which invention I hereunto set my hand:

HUGO BILGRAM.
